TELEPHONE CALL RECORDER

Heinz Recker, Ridgewood, N. J., assignor to
Theodore Reiss, Brooklyn, N. Y.

Application January 9, 1939, Serial No. 249,877

18 Claims. (Cl. 179—7)

My present invention relates to counting mechanism and more particularly to such as are adapted to register completed calls made on dial-operated telephones.

It is the main object of my invention to provide a device of the general character indicated which is simple in construction, easy and economical to fabricate and assemble and which is admirably adapted to perform the intended functions as hereinafter more fully set forth.

It is another object of the present invention to provide a call counter which is fool-proof in that the operation of the dial while the receiver is still on the "hook" will have no effect upon the counting mechanism.

It is still another object of the present invention to provide a device which is further fool-proof in that with the receiver off the "hook," the counting mechanism will still fail to function in the event that the dialing is not completed or the receiver is returned to the "hook" prior to completing said dialing.

It is still a further object of the present invention to provide a device which is additionally fool-proof in that even though the dialing of a telephone number is completed, the counting mechanism will not function in the event that the user gets a "busy signal."

These and other objects and advantages of the device of the present invention will readily occur to those skilled in the art to which the present invention relates as the detailed description thereof progresses.

In the accompanying specification, I shall describe and in the annexed drawings show, an illustrative embodiment of the counting mechanism of the present invention. It is however to be clearly understood that I do not wish to be limited to the exact details herein shown for purposes of illustration only, inasmuch as changes may be made therein without the exercise of invention and within the scope of the claims hereto appended.

In the accompanying drawings,

Fig. 1 is a front elevational view of a "French" type dial telephone having the receiver thereof removed and showing the aforesaid illustrative embodiment of the present invention attached thereto;

Fig. 2 is a side elevational view of the same;

Fig. 3 is an enlarged, plan view of the aforesaid illustrative embodiment of the present invention having the cover plate removed to show the inner construction, the device being shown in its "initial" condition prior to dialing;

Fig. 4 is a transverse sectional view taken along line 4—4 of Fig. 3;

Fig. 5 is a fragmentary, transverse sectional view taken through the center of the driving mechanism constituting a part of the aforesaid illustrative embodiment of the present invention;

Fig. 6 is a fragmentary view similar to Fig. 3 showing the device in an "operative" condition just prior to completing the dialing of a call;

Fig. 7 is a fragmentary projection, in plan, of Fig. 6;

Fig. 8 is a fragmentary, transverse sectional view taken through the tripping mechanism constituting a part of the aforesaid illustrative embodiment of the present invention, and showing the same in an "intermediate" condition; and

Fig. 9 is a view similar to Fig. 8 showing the tripping mechanism in a "fully operative" condition.

Referring now more in detail to the aforesaid illustrative embodiment of the present invention and with particular reference to Figs. 1, 2, and 3 of the drawings, the numeral 10 generally designates a "French" type dial telephone which includes a base 11 from which rises a neck 12 having formed at the top thereof a receiver cradle 13. Adapted to rest within the cradle 13, upon the conventional receiver "hook" 14, is a receiver, not shown in the drawings for the purpose of clarity. Associated with the telephone 10 is the usual rotatable dial 15 and the finger stop 16 for controlling the extent of dialing.

Attached to the telephone 10 is the registering mechanism 10' which is housed within a casing 17 shaped so as to conform with the shape of the telephone, the casing being secured to the telephone by means of a collar 18 engaged with the neck 12 and a pivotally mounted catch member 19, one end 20 of which engages the finger stop 16 and holds the same within a recess 21 formed in the casing wall, the other end of the catch member being provided with the cam surface 22 which has cooperable therewith a set screw 23. The arrangement is such that by rotating the set screw 23 in a clockwise direction, its inner end operates against the cam surface 22 of the catch member 19 to pivot the latter so that its end 20 firmly holds the finger stop 16 within the recess 21.

Referring now particularly to Figs. 3 to 6 inclusive of the drawings, the numeral 24 designates a bell-crank lever pivotally mounted upon a shaft 25, the lever being provided with an arm 26 which is bifurcated at the outer end thereof so as to carry a spring-pressed dog 27 adapted

- to be engaged, in a manner to be hereinafter more fully explained, by a lug 28, affixed to the dial 15 of the telephone by straddling the first dial opening 29. It is preferred that the lug 28 be so affixed 5 to the dial 15 that it cannot be removed without the use of a special wrench; for, if this is not the case, the telephone may be used by removing the lug 28 and therefore not counting the calls made.
- 10 The bell-crank lever 24 is provided with another arm 30, the end of which is likewise bifurcated so as to carry a spring-pressed pawl 31 normally resting against a stop 32 which limits the downward movement thereof.
- 15 Also pivotally mounted upon the shaft 25, adjacent the lever 24, is a toothed sector 33 provided with a pin 34 extending into the path of the arm 26 of the lever 24, in contact with the lower edge of the said arm, the sector being further provided with another pin 35, extending outwardly from the opposite face of the sector which carries the pin 34. Formed with the sector 33 is a collar 36 and at the outer end of the collar, there is integrally formed, a bar 37. Immediately 20 adjacent the bar 37 and pivotally mounted upon the shaft 25 is another bell-crank lever 38, said lever consisting of an arm 39 provided, near the outer end thereof with a pin 40 which extends outwardly from both sides of the arm 39, the extension on one side being in the path of the bar 37, in contact with the upper edge thereof. The lever 38 includes another arm 41 which constitutes a catch member to set or cock the counting mechanism preparatory to recording the completed call as will hereinafter be more fully explained.
- 30 The toothed sector 33 engages a pinion 42 integrally formed with a shaft 43 rotatably mounted in the casing 17, the end of the shaft 43 opposite the pinion 42 constituting an anchor for the inner end of a coil spring 44, the other or outer end of which is fixed to a spring housing 45. Loosely mounted upon the shaft 43 is a sleeve 46 having affixed thereto a gear 47 which carries a spring-pressed pawl 48 engaged with the pinion 42 in such a way that the pinion is free to rotate in a clockwise direction without effecting the gear 47 but adapted to constitute a link between the pinion 42 and the gear 47 so that rotation of the pinion in a counter-clockwise direction similarly rotates the gear. The gear 47 meshes with a pinion 49 affixed upon a shaft 50 which also has affixed thereon a gear 51 in mesh with a pinion 52 affixed upon a shaft 55. The shaft 53 also has affixed thereon an escapement wheel 54 controlled by a pivotally mounted escapement 55. The purpose of the gear train just described is to control the speed with which the coil spring 44 unwinds after it has 60 been wound to an operable condition by the action of the sector 33 upon the pinion 42.

Referring now particularly to Figs. 3, 4, and 6 to 9 inclusive, I have shown a conventional counter mechanism 56 controlled by a counter shaft 65 57 which has affixed thereto a counter arm 58 maintained in constant contact with the pin 40 of the arm 39, on the side opposite the bar 37, under the action of the spring 59.

Pivotally mounted upon the same center as 70 the counter arm 58 is a ratchet wheel 60 provided with a multiplicity of teeth 61, one of which, 62, is a half tooth, the ratchet wheel being operable, in a manner to be hereinafter described, by means of the pawl 31 constituting part of 75 the lever 24. The ratchet wheel 60 is normally

urged in a counter-clockwise direction by means of a spring, not shown in the drawings. During the operation of the device, it is necessary to prevent the spring just mentioned from urging the ratchet wheel 60 to its normal, inoperative position and in order to do this, I provide a dog 63 formed on a spring-pressed pivotally mounted bar 64, the dog 63 being normally maintained out of contact with the ratchet wheel 60 in view of the fact that the arm 64 is in contact with the lower edge of the bar 37. The ratchet wheel 60 carries a pin 65 which, during the normal, inoperative position of the ratchet wheel is in contact with the underside of a stop 66.

The pin 65 is adapted, during the course of 15 the operation of the device, as will hereinafter be more fully explained, to engage a depending tail 67 formed on a slide 68 mounted in a U-shaped bracket 69 carried in the casing, one of the openings 70 of the bracket 69 being enlarged so that 20 the slide 68 can move arcuately as well as laterally. The slide 68 is provided with a stop 71 which is normally in contact with a portion of the bracket 69, the slide being maintained in this position by means of expansion spring 72, one end 25 of which urges against a portion of the bracket 69 and the other end of which urges against a lug 73 struck up from the body of the slide itself.

Pivotally mounted in the casing, above the slide 68, near the end thereof opposite the tail 30 67, is a spring-pressed latch 74 adapted, as will hereinafter be more fully described, to be actuated by a tripping dog 75 pivoted at 76 to a lever 77 in turn pivotally mounted in a bearing 78 formed in the casing. In order to permit the 35 arcuate movement of the lever 77 and at the same time conserve space, I provide the latch member 74 with a notch 79 and in order to control, as will hereinafter be more fully described, the operation of the tripping dog, 75, I provide 40 the slide 68 with a notch 80.

At the end of the lever 77 opposite that which carries the tripping dog 75, I provide a coupling 81 by means of which the lever 77 is pivotally connected with a rod 82 extending upwardly 45 through a tubular extension 83 of the casing 17, the rod 82 having affixed to the upper end thereof of a plate 84 adapted to overlie the "hook" 14, as most clearly seen in Figs. 1 and 2 of the drawings. 50

This completes the description of the aforesaid illustrative embodiment of the present invention and its operation and mode of use may be summarized as follows:

With the receiver on the "hook" the positions 55 of the various elements of the present invention are seen in Figs. 3 and 4. As soon as the receiver is removed from the "hook," the "hook" moves upwardly to close the circuit through the telephone so as to permit a call to be made. This movement of the "hook" 14 is transmitted through the plate 84, connecting rod 82, coupling 81, and lever 77 to the tripping dog 75 so as to move the latter into a position where its operating end will be beneath the latch member 74. 60 With the device in this condition a call can now be made.

As the dial 15 is operated for the first time, the lug 28 comes into contact with the dog 27 and pivots the lever 24. When the lug 28 reaches a 70 certain point in the course of its arcuate movement, it clears the dog 27 so as to permit the pivotally mounted lever 24 to return, by its own weight, to its normal position. On the return movement of the lug 28, said lug will come into 75

contact with the under edge of the dog 21 and merely pivot the same out of the way so as to permit the lug to pass it by and be ready for the next movement of the dial 15.

5 The operation of the lever 24 accomplishes two things. In the first place the pawl 31 comes into contact with the teeth of the ratchet wheel 60 and rotates the same the distance of one tooth. In the second place, because of the contact between the arm 26 of the lever 24 and the pin 34, the toothed sector 33 is pivoted upon the shaft 25 so as to rotate the pinion 42 and so store up energy in the spring 44. When the sector 33 pivots under the urging of the arm 15, the bar 37 is likewise pivoted so as to release the bar 64 and permit the dog 63 to engage the ratchet wheel 60 and prevent the return movement thereof. At the same time the bar 37, through the pin 40, raises the arm 39 so as to 10 pivot the bell-crank lever 38 and thus move the other arm 41 of the said bell-crank lever into such a position that it is engaged by the latch member 74. Until the latch member is tripped, as will hereinafter be described, the lever 38 is 15 maintained in its locked position. The upward movement of the arm 39 also raises the counter arm 58 so as to set or cock the counting mechanism 56 to register a call upon the release of the arm 58. The position of the parts in their 20 so-called cocked position will be more fully understood by reference to Fig. 6 of the drawings. It is to be understood that the various movements and conditions just described are all brought about upon the first movement of the dial 15 of 25 the telephone.

30 The next movement of the dial will, through the lever 24, operate the ratchet wheel 60 so as to move the same the distance of another tooth and, assuming that it takes seven dialings to 35 make a call, as is the case in New York City, the ratchet wheel 60 will be rotated the distance of one tooth each time that the dial is operated until the seven dialings have been made. If any further dialings are made, the pawl 31 will encounter the half tooth 62 as a result of which the ratchet wheel 60 will not be further rotated.

40 When the ratchet wheel 60 is rotated the distance of one tooth for the seventh time, the pin 65 will come into contact with the tail 67 of the 45 slide 68 and move the slide 68 to the right, in Fig. 3 or 6, against the action of the spring 72. This movement of the slide 68 will take the notch 80 out of register with the tripping dog 75, it being understood that when the mechanism is 50 not in use, this notch is in register with the dog, so that upon the happening of the following, the dog 75 will be in condition to trip the latch member 74.

I have arranged the spring 44 and the train 55 of gears which controls the unwinding thereof in such a manner that it takes 30 seconds for the sector 33 to return to its normal position after the seventh dialing has been made. The purpose of this will be explained.

60 As the spring 44 unwinds, the pinion 42 drives the train 47, 49, 50, 52, 54, and 55, the train controlling, as has been stated, the speed with which the spring unwinds. The counter-clockwise movement of the pinion 42 returns the sector 33 to 65 its normal position shown in Fig. 3 of the drawings. As the sector reaches the end of its return movement the pin 35 carried thereby comes into contact with the underside of the slide 68, and lifts the same arcuately upwardly so as to 70 transmit an upward movement to the tripping

75 dog, 75. The dog in turn lifts the latch member 74 to release the arm 41 of the lever 38 and the releasing of this lever permits the counter arm 58 to return to its normal, downward position, thus operating the counting mechanism 56 to 5 record the call. Upon the return of the sector 33 to its normal, inoperative position, the dog 63 is moved out of engagement with the ratchet wheel 60 and the latter returns to its normal position and the return of this member to its 10 normal position permits the slide 68 to likewise return to its normal position.

This completes the description of the normal operation of the aforesaid illustrative embodiment of the present invention in the course of making 15 a conventional call. It is to be noted that in order that the counter mechanism operate to register a call, there are two conditions that the device must be in or else the call will not be counted. In the first place, the receiver must be 20 off the "hook" so as to move the tripping dog 75 to its operative position beneath the latch member 74. If the dial is operated while the receiver is on the "hook," no call can be counted for the reason that, even though the counter arm 58 is 25 cocked to a position permitting the operation of the counter mechanism 56, any upward movement of the tripping dog 75 will not be transmitted to the latch member 74 and so the counter arm 58 will not be released. In addition, unless 30 the notch 80 is out of register with the tripping dog 75, no call can be counted for the reason that any upward movement of the slide 68 will not be transmitted to the tripping dog 75 unless the dog and notch are out of register. In order that 35 the dog and notch be out of register, it is necessary that the dial be operated seven times, for without this, the pin 65 will not engage the tail 67 to move the slide 68.

40 Because of these fool-proof features, dialing when the receiver is on the "hook" will not bring about registering of a call even though the dial be operated seven times. Also, though the receiver be off the "hook," a call will not be counted if the dial has not been operated seven times, in 45 other words, less than the number of times necessary to make a call. Finally, because of the timing feature above described, even though the receiver has been off the "hook" and the dial has been operated seven times, a call will not be registered if the receiver is returned to the "hook" before the completion of the return movement of the sector 33 which, as above stated, takes place 30 seconds after the seventh dialing has been made. This will enable the user to "hang up" if 50 a busy signal is obtained. Obviously if this amount of time is deemed insufficient, minor adjustment of the device can be made so as to change the time to any particular amount desired.

55 This completes the description of the mode of operation and use of the aforesaid illustrative embodiment of the present invention and it will be noted from all of the foregoing that the device is simple in construction, easy and economical to fabricate and assemble and admirably 60 adapted to perform the intended functions, particularly in so far as the same relates to the fool-proof nature of the device.

65 Other objects and advantages will readily occur to those skilled in the art to which the present 70 invention relates.

75 What I claim as my invention is:

1. In combination with a dial telephone and a counter mechanism, means, actuated by the operation of the dial of the telephone, to cock 75

the counter mechanism preparatory to registering a call, means to release said first named means to complete the registering of the call, means to control the time consumed by the operation of said second named means, and master means, associated with the "hook" of the telephone, to render said second named means operative only when the receiver of the telephone is off the "hook."

10 2. In combination with a dial telephone and
a counter mechanism, means, actuated by the
operation of the dial of the telephone, to cock
the counter mechanism preparatory to register-
ing a call, said means, including a latch mem-
15 ber, and a catch member associated with the
counter mechanism, adapted to be engaged by
said latch member, means to release said first
named means to complete the registering of the
call, means to control the time consumed by
20 the operation of said second named means, and
master means, associated with the "hook" of the
telephone, to render said second named means
operative only when the receiver of the telephone
is off the "hook."

25 3. In combination with a dial telephone and
a counter mechanism, means, actuated by the
operation of the dial of the telephone, to cock
the counter mechanism preparatory to register-
ing a call, means to release said first named
30 means to complete the registering of the call,
said second named means including a tripping
dog, means cooperable with said dog to actuate
the same, and means, actuated by the operation
of the dial of the telephone to render said last
35 named means effective only upon the dialing of
a complete call, means to control the time con-
sumed by the operation of said second named
means, and master means, associated with the
"hook" of the telephone, to render said second
40 named means operative only when the receiver
of the telephone is off the "hook."

4. In combination with a dial telephone and a counter mechanism, means, actuated by the operation of the dial of the telephone, to cock
45 the counter mechanism preparatory to registering a call, means to release said first named means to complete the registering of the call, means to control the time consumed by the operation of said second named means, said last
50 named means including an escapement-controlled gear train associated therewith, and master means, associated with the "hook" of the telephone, to render said second named means operative only when the receiver of the telephone
55 is off the "hook."

5. In combination with a dial telephone and a counter mechanism, means, actuated by the operation of the dial of the telephone, to cock the counter mechanism preparatory to registering a call, means to release said first named means to complete the registering of the call, means to control the time consumed by the operation of said second named means, and master means, associated with the "hook" of the telephone, to render said second named means operative only when the receiver of the telephone is off the "hook," said master means including a series of levers having a portion thereof overlying the "hook" of the telephone and adapted to move a portion of said second named means into and out of operative positions.

6. In combination with a dial telephone and a counter mechanism, means, actuated by the operation of the dial of the telephone, to cock the counter mechanism preparatory to registering

a call, means to release said first named means to complete the registering of the call, said second named means including a tripping dog, a slide mechanism associated with said dog and having a notch therein normally in register with said dog, and means, actuated by the operation of the dial of the telephone, to move said slide so that the notch thereof and said dog are not in register only upon the dialing of a complete call, means to control the time consumed by the operation of said second named means, and master means, associated with the "hook" of the telephone to render said second named means operative only when the receiver of the telephone is off the "hook." 15 10 15

7. In combination with a dial telephone and a counter mechanism, means, actuated by the operation of the dial of the telephone, to cock the counter mechanism preparatory to registering a call, said means including a latch member, and 20 a catch member associated with the counter mechanism, adapted to be engaged by said latch member, means to release said first named means to complete the registering of the call, said second named means including a tripping 25 dog adapted to operate the latch member of said first named means, means cooperable with said dog to actuate the same, and means, actuated by the operation of the dial of the telephone to render said last named means effective only 30 upon the dialing of a complete call, means to control the time consumed by the operation of said second named means and master means, associated with the "hook" of the telephone, to render said second named means operative only 35 when the receiver of the telephone is off the "hook."

8. In combination with a dial telephone and a counter mechanism, means, actuated by the operation of the dial of the telephone, to cock the counter mechanism preparatory to registering a call, said means, including a latch member, and a catch member associated with the counter mechanism, adapted to be engaged by said latch member, means to release said first named means to complete the registering of the call, means to control the time consumed by the operation of said second named means, said last named means including an escapement-controlled gear train associated therewith, and master means, associated with the "hook" of the telephone, to render said second named means operative only when the receiver of the telephone is off the "hook." 40 45 50

9. In combination with a dial telephone and 55
a counter mechanism, means, actuated by the
operation of the dial of the telephone, to cock
the counter mechanism preparatory to register-
ing a call, said means, including a latch mem- 60
ber, and a catch member associated with the
counter mechanism, adapted to be engaged by
said latch member, means to release said first
named means to complete the registering of the
call, means to control the time consumed by the, 65
operation of said second named means, and mas-
ter means, associated with the "hook" of the tele-
phone, to render said second named means op-
erative only when the receiver of the telephone
is off the "hook," said master means including 70
a series of levers having a portion thereof over-
lying the "hook" of the telephone and adapted
to move a portion of said second named means
into and out of operative positions.

10. In combination with a dial telephone and a counter mechanism, means, actuated by the 75

operation of the dial of the telephone, to cock the counter mechanism preparatory to registering a call, said means, including a latch member, and a catch member associated with the counter mechanism, adapted to be engaged by said latch member, means to release said first named means to complete the registering of the call, said second named means including a tripping dog adapted to actuate the latch member of said first 5 named means, a slide mechanism associated with said dog and having a notch therein normally in register with said dog, and means, actuated by the operation of the dial of the telephone, to move said slide so that the notch thereof and said dog 10 are not in register only upon the dialing of a complete call, means to control the time consumed by the operation of said second named means, and master means, associated with the "hook" of the telephone, to render said second 15 named means operative only when the receiver of the telephone is off the "hook."

11. In combination with a dial telephone and a counter mechanism, means, actuated by the operation of the dial of the telephone, to cock the counter mechanism preparatory to registering a call, means to release said first named means to complete the registering of the call, said second named means including a tripping dog, means cooperable with said dog to actuate the same, and means, actuated by the operation of the dial of the telephone to render said last named means effective only upon the dialing of a complete call, means to control the time consumed by the operation of said second named 30 means, said last named means including an escapement-controlled gear train associated therewith, and master means, associated with the hook of the telephone, to render said second named means operative only when the receiver of the telephone is off the "hook."

12. In combination with a dial telephone and a counter mechanism, means, actuated by the operation of the dial of the telephone, to cock the counter mechanism preparatory to registering a call, means to release said first named means to complete the registering of the call, said second named means including a tripping dog, means cooperable with said dog to actuate the same, and means, actuated by the operation of the dial of the telephone to render said last named means effective only upon the dialing of a complete call, means to control the time consumed by the operation of said second named means, and master means, associated with the "hook" of the telephone, to render said second named means operative only when the receiver of the telephone is off the "hook," said master means including a series of levers having a portion thereof overlying the "hook" of the telephone and adapted to move a portion of said second named means into and out of operative positions.

13. In combination with a dial telephone and a counter mechanism, means, actuated by the operation of the dial of the telephone, to cock the counter mechanism preparatory to registering a call, means to release said first named means to complete the registering of the call, means to control the time consumed by the operation of said second named means, said last named means including an escapement-controlled gear train associated therewith, and master means, associated with the "hook" of the telephone, to render said second named means operative only when the receiver of the telephone is off the "hook," said master means including a

series of levers having a portion thereof overlying the "hook" of the telephone and adapted to move a portion of said second named means into and out of operative positions.

14. In combination with a dial telephone and a counter mechanism, means, actuated by the operation of the dial of the telephone, to cock the counter mechanism preparatory to registering a call, means to release said first named means to complete the registering of the call, said second named means including a tripping dog, means cooperable with said dog to actuate the same, and means, actuated by the operation of the dial of the telephone to render said last named means effective only upon the dialing of a completed call, means to control the time consumed by the operation of said second named means, said last named means including an escapement-controlled gear train associated therewith, and master means, associated with the "hook" of the telephone, to render said second named means operative only when the receiver of the telephone is off the "hook."

15. In combination with a dial telephone and a counter mechanism, means, actuated by the operation of the dial of the telephone, to cock the counter mechanism preparatory to registering a call, means to release said first named means to complete the registering of the call, said second named means including a tripping dog, a slide mechanism associated with said dog and having a notch therein normally in register with said dog, and means, actuated by the operation of the dial of the telephone, to move said slide so that the notch thereof and said dog are not in register only upon the dialing of a complete call, means to control the time consumed by the operation of said second named means, and master means, associated with the "hook" of the telephone to render said second named means operative only when the receiver of the telephone is off the "hook."

16. In combination with a dial telephone and a counter mechanism, means, actuated by the operation of the dial of the telephone, to cock the counter mechanism preparatory to registering a call, said means including a latch member, a catch member associated with the counter mechanism and adapted to be engaged by said latch member, and a series of levers intermediate said catch member and the dial of the telephone and operable by the latter, means to release said first named means to complete the registering of the call, said second named means including a tripping dog adapted to operate the latch member of said first named means, means cooperable with said dog to actuate the same, and means, actuated by the operation of the dial of the telephone to render said last named means effective only upon the dialing of a complete call, means to control the time consumed by the operation of said second named means, said last named means including an escapement-controlled gear train associated therewith, and master means, associated with the "hook" of the telephone, to render said second named means operative only when the receiver of the telephone is off the "hook."

17. In combination with a dial telephone and a counter mechanism, means, actuated by the

operation of the dial of the telephone, to cock the counter mechanism preparatory to registering a call, said means including a latch member, a catch member associated with the counter mechanism and adapted to be engaged by said latch member, and a series of levers intermediate with said catch member and the dial of the telephone and operable by the latter, means to release said first named means to complete the registering of a call, said second named means including a tripping dog adapted to operate the latch member of said first named means, means cooperable with said dog to actuate the same, and means, actuated by the operation of the dial of the telephone to render said last named means effective only upon the dialing of a complete call, means to control the time consumed by the operation of said second named means and master means, associated with the "hook" of the telephone, to render said second named means operative only when the receiver of the telephone is off the "hook," said master means including a series of levers having a portion thereof overlying the "hook" of the telephone and adapted to move a portion of said second named means into and out of operative positions.

18. In combination with a dial telephone and a counter mechanism, means, actuated by the operation of the dial of the telephone, to cock the counter mechanism preparatory to registering a call, means to release said first named means to complete the registering of the call, said second named means including a tripping dog, means cooperable with said dog to actuate the same, and means, actuated by the operation of the dial of the telephone to render said last named means effective only upon the dialing of a complete call, means to control the time consumed by the operation of said second named means, said last named means including an escapement-controlled gear train associated therewith, and master means, associated with the "hook" of the telephone, to render said second named means operative only when the receiver of the telephone is off the "hook," and master means including a series of levers having a portion thereof overlying the "hook" of the telephone and adapted to move a portion of said second named means into and out of operative positions.
